UNITED STATES PATENT OFFICE.

WILLIAM J. WRIGHT, OF PITTSBURG, PENNSYLVANIA, ASSIGNOR TO JOHN S. SCULLY, OF PITTSBURG, PENNSYLVANIA.

WIRE-WEAVING MACHINE.

SPECIFICATION forming part of Letters Patent No. 711,809, dated October 21, 1902.

Application filed January 18, 1902. Serial No. 90,288. (No model.)

To all whom it may concern:

Be it known that I, WILLIAM J. WRIGHT, a citizen of the United States, residing at Pittsburgh, in the county of Allegheny and State of Pennsylvania, have invented certain new and useful Improvements in Wire-Weaving Machines, of which the following is a specification, reference being had therein to the accompanying drawings, forming part of this specification, in which—

Figure 1 is a view, partly in section and partly in elevation, of my improved wire-weaving machine on the line I I of Fig. 2. Fig. 2 is a sectional plan view thereof, indicated by the line II II of Fig. 1. Fig. 3 is a sectional view on the line III III of Fig. 1. Fig. 4 is a horizontal sectional view on the line of section of Fig. 2, illustrating the cam-operated clutch mechanism thrown out of engagement by which the feeding-rolls remain stationary during the shearing operation. Fig. 5 is an end view of the machine. Fig. 6 is a cross-sectional view on the line VI VI of Fig. 1. Fig. 7 is a detail sectional view of the knife and its operating mechanism, showing the shearing operation. Fig. 8 is a cross-sectional view through the feeding-rolls, spindles, and shear, on an enlarged scale, illustrating more fully the construction shown in the upper portion of Fig. 6. Fig. 9 is a detail plan view illustrating the relative arrangement of the coiling-guides and the spindles. Fig. 10 is a cross-sectional view on the line X X of Fig. 9, illustrating the arrangement of the spindles and the intervening coiling-guides.

My invention consists of an improved machine for weaving wire into fabric or netting composed of interfitting spiral coils, whereby the full width of the netting desired may be made at one time of any desired number of wires simultaneously and continuously and in one operation. Heretofore in making wire-work of this description it has been the practice to form either a single spiral coil upon a forming-spindle by interweaving such coils into the last woven coil of a connected series or by making two interfitting spiral coils upon a forming-spindle and then joining pairs of such interwoven coils by a single coil and

continuing such operation until the required width was obtained.

In the practice of my invention I employ a plurality of spindles 2, having the usual spiral grooves 3, which spindles are mounted in suitable housings or frames 4 at such a distance apart as will admit of the location between the spindles of separate coiling-guides 5, which for approximately the full length of the spindle are straight. These guides have on one side a groove 6, of sufficient size to admit the wires, but partly closed, so as to not allow the wires to escape outwardly, and at or beyond the delivery end of the spindles each of these guides is formed into a spiral 7 of the same pitch and relative position as the spiral grooves 3 of the spindles, the groove 6 of the guides being maintained on the inner side, as shown.

By reason of the close arrangement of the pairs of spirals formed on the spindle 2 to the next adjacent pair similarly formed it will be seen that the spiral guide 7 may be located as to the alternate opposite spiral loops of such pairs without interference with the forward progress of the coils, whereby when the independent spiral coils 8 are finally delivered from the ends of the guides 7 they will travel forward in the same relation to the coils 9 10 from spindles 2 and will engage with such coils, as by reason of the close proximity of each independent pair 9 10 sufficient clearance is allowed for free engagement and interaction, and it will be seen that such assemblage and interaction of the coils will be continuous throughout the operation. The forward feed of the wire is accomplished by means of upper and lower feed-rolls 11, mounted in suitable housings 12, the rolls being geared together by toothed gearing 13, so as to operate simultaneously and at uniform speed. Motion is transmitted to one of the rolls through a toothed wheel 14 in engagement with a similar wheel 15, mounted upon the main shaft 16 and adapted to be intermittently thrown into gear with such shaft by means of interfitting clutch members 17 18, the clutch 18 being automatically operated by means of lever 19 in engagement with it and operated by cam 20 on shaft 21. The

shaft 21 is rotated at slow speed through pinion 22 on its outer end in mesh with a driving-pinion 23, mounted upon the outer end of a spindle 24, which is adjustably set in the 5 segmental slot 25 in the housing, which permits the spindle 24 to be set toward or from the main shaft 16, so as to permit of the insertion of gears of different sizes, so as to vary the relative speed of the main shaft and 10 feed-rolls and shaft 21, by which the shearing mechanism is operated, whereby the machine may be set to cut off different lengths as desired. Power is imparted to the driving-pinion 23 through toothed wheel 27, mounted 15 upon spindle 24, preferably secured to pinion 23, the pinion 27 being in mesh with driving-pinion 28 on the opposite end of the main shaft 16. Such main shaft is driven by belt or other connections through pulleys 29 or 20 other suitably-connected mechanism from any desired source of power.

Upon shaft 21, carrying cam 20, are mounted cams 30 on the inside of the end bearings of the shaft, which cams for three-quarters of 25 their periphery are of uniform diameter, the other quarter being formed into the cam projection 31, which projection in the rotation of the cam depresses the end 23 of lever 33, pivoted at 34 to the frame and provided with 30 a pivotally-connected pitman 35, attached to and for the purpose of operating the knife-beam 36, mounted in vertical slideways at each end of the machine. The lever 33 is provided with a counterweight *w*, by which 35 the depressing action of the cam is reversed and the shear-beam raised.

The construction of the cam, lever, and connections therefrom to the knife is, as shown, the same at each end of the machine to insure 40 uniform action.

The shear-beam is provided with knife 37, which slides upon the outer face of stationary shear 38, through openings 39 of which the woven netting passes outwardly from the 45 weaving spindles.

The clutch 18 is held in engagement with the member 17, so as to transmit rotatory movement to the rolls to feed the wires during three-fourths of the revolution of shaft 21 by 50 reason of the relative arrangement of the cams 20 and 30. The clutch is thrown out of gear during the downward travel of the knife, so that the feeding-rolls remain stationary for one-fourth of the revolution of shaft 21 55 or until the shearing action is completed, the shearing-knife being raised simultaneously with the renewed clutching engagement produced by cam 20. As thus constructed, the individual wires are fed inwardly between 60 the rolls to the spindles, and the operation is continuous and automatic, the rolls feeding forward the desired length of netting, which is sheared off at suitable intervals, as I have described, without further attention from the 65 operator than from time to time to renew wire to the spools (not shown) as the same become emptied.

The machine is capable of a very greatly-increased output over the present method of weaving wire-netting and will be appreciated 70 by those familiar with the art.

The machine is very compact and simple in construction, not liable to get out of order, and may be operated by one capable of exercising ordinary skill. The size of the mesh 75 may be varied by the substitution of various sizes of spindles and guides, and such changes, as well as other variations, may be made by the skilled mechanic without departing from my invention, since I do not desire to be confined to the specific construction as shown and described, but to include all such changes and variations as are within the scope of the following claims.

What I claim is—

1. In a machine for weaving wire, the combination of feed-rolls, a plurality of grooved spindles with intervening interlooping guides, means for operating the feed-rolls, and an intermittently-actuated shear.

2. In a machine for weaving wire, the combination of feed-rolls, a plurality of grooved spindles with intervening interlooping guides, a shear-knife, means for operating the feed-rolls and for periodically stopping them, and 95 means for operating the shear-knife during the inaction of the feed-rolls.

3. In a machine for weaving wire, the combination of feed-rolls, a plurality of grooved spindles with intervening interlooping guides 100 in advance of the feed-rolls, a shear-knife and means for intermittently actuating the feed-rolls and the shear-knife respectively.

4. In a machine for weaving wire, the combination of feed-rolls, housings therefor, a 105 main shaft, means for intermittently transmitting power from the main shaft to the feed-rolls, a plurality of grooved spindles with intervening interlooping guides in advance of the feed-rolls, a shear in advance of such 110 grooved spindles and guides, and means for intermittently operating the shear.

5. In a machine for weaving wire, the combination of feed-rolls, housings therefor, a main shaft, means for intermittently transmitting power from the main shaft to the feed-rolls, a plurality of grooved spindles with intervening interlooping guides in advance of the feed-rolls, a shear in advance of such grooved spindles and guides, a counter-shaft provided with cams, and means operated by such cams for intermittently actuating the shear-knife, substantially as set forth.

6. In a machine for weaving wire, the combination of feed-rolls, housings therefor, a 125 main shaft, means for intermittently transmitting power from the main shaft to the feed-rolls, a plurality of grooved spindles with intervening interlooping guides in advance of the feed-rolls, a shear in advance of 130 such grooved spindles and guides, a counter-shaft provided with cams, and means operated by such cams for intermittently actuating the shear-knife, and means for automat-

ically raising the shear-knife, substantially as set forth.

7. In a machine for weaving wire, the combination of a main frame, feed-rolls mounted therein, a plurality of grooved spindles with intervening interlooping guides in advance of the feed-rolls, a shear-knife in advance of the grooved spindles and guides, a constantly-revolving main shaft, means for intermittently operating the feed-rolls from such shaft, a counter-shaft driven by such main shaft, and means for intermittently actuating the shear-knife through such counter-shaft in conformity with the intermittent action of the feed-rolls, substantially as set forth.

15 8. In a machine for weaving wire, the combination of a main frame, feed-rolls mounted therein, a plurality of grooved spindles with

intervening interlooping guides in advance of the feed-rolls, a shear-knife in advance of the 20 grooved spindles and guides, a constantly-revolving main shaft, means for intermittently operating the feed-rolls from such shaft, a counter-shaft driven by such main shaft, and means for intermittently actuating 25 the shear-knife, through such counter-shaft in conformity with the intermittent action of the feed-rolls, and means for retracting the shear-knife, substantially as set forth.

In testimony whereof I affix my signature 30 in presence of two witnesses.
